DESIGN FOR A LAWN SPRINKLER

Armand De Mott, Fords, N. J.

Application July 7, 1945, Serial No. 120,557

Term of patent 3½ years

(Cl. D91—1)

To all whom it may concern:

Be it known that I, Armand De Mott, a citizen of United States, residing in Fords, county of Middlesex, and State of New Jersey, have invented a new, original, and ornamental Design for a Lawn Sprinkler, of which the following is a specification, reference being had to the accompanying drawing, forming a part thereof.

Fig. 1 is a top plan view of a lawn sprinkler embodying my new design, and

Fig. 2 is a side elevational view thereof.

I claim:

The ornamental design for a lawn sprinkler, as shown.

ARMAND DE MOTT.
